(57) **CLAIM**

The ornamental design for an injection device, as shown and described.

DESCRIPTION

1. Injection device.

1.1 : Perspective

1.2 : Perspective

1.3 : Perspective

1.4 : Perspective

1.5 : Perspective

1.6 : Front

1.7 : Front view, deployed

1.8 : Back

1.9 : Top

1.10 : Bottom

1.11 : Left

1.12 : Right

The shape of the claimed design is elongated with height larger than width and width larger than depth; the front side features a rounded push-button and a rectangular display screen; on the left side is an oval power on-off button, a semi-rectangular cartridge door button with upper rounded edges, and a partially transparent rectangular cartridge door, deploy-able as shown in Fig. 1.7; on the bottom is a circular needle cavity surrounded by four elongated and curved anti-slip coverings, and an essentially rectangular battery cover that also partially fits the outer shape of the product; on the back are three protrusions for better grip, a rounded space intended to the device's labeling, and a bracket-like strap fixation means; on the right is a semi-rectangular push-button with upper rounded edges.
